(57) **CLAIM**

The ornamental design for a table, as shown and described.

DESCRIPTION

FIG. 1 is a perspective view of a table according to the invention;

FIG. 2 is a top view of the table of FIG. 1;

FIG. 3 is a bottom view of the table of FIG. 1;

FIG. 4 is a left side view of the table of FIG. 1, with the right side view being a mirror image thereof;

FIG. 5 is front view of the table of FIG. 1; and,

FIG. 6 is a rear view of the table of FIG. 1.

Portions of the table shown in broken lines form no part of the claimed design.

1 Claim, 4 Drawing Sheets(56)
